UNITED STATES PATENT OFFICE.

WILLIAM A. LILLIENDAHL, OF JERSEY CITY, NEW JERSEY.

SUPPORT FOR STEAM-PIPES.

SPECIFICATION forming part of Letters Patent No. 361,767, dated April 26, 1887.

Application filed January 25, 1886. Serial No. 189,585. (No model.)

To all whom it may concern:

Be it known that I, WILLIAM A. LILLIENDAHL, of Jersey City, in the county of Hudson and State of New Jersey, have invented 5 an Improvement in Supports for Steam-Pipes, of which the following is a specification.

The object of this invention is to protect the wood-work of buildings from the heat of steam-pipes. It has been found that where 10 wood-work is continuously exposed to the action of heat—such as in ordinary steam-heating apparatus, where the temperature ranges from 212° to 250°—the wood-work becomes charred to such an extent that it will ignite under 15 favorable atmospheric conditions.

My present invention relates to an improvement in the fastenings and supports for steam-pipes, in which I use a sectional ring of slate, soapstone, or similar material of inferior con- 20 ductivity between the steam-pipe and the metallic sectional ring that is attached to the wood-work, thus allowing the parts to be put around the pipe after it is in place, and lessening the risk of charring the wood-work, and 25 at the same time avoiding the objectionable noise that is often made by the steam-pipes as they slide upon the metallic supports in consequence of the expansion or contraction due to changes of temperature.

30 In the drawings, Figure 1 is a vertical section representing the improved supports as applied to a vertical steam-pipe. Fig. 2 is a plan of the floor-support, and Fig. 3 is a plan of the ceiling-support.

35 The metallic stock A is in the form of a divided ring, to which is applied the divided support B, made of soapstone, slate, or similar material. With a stock that is adapted to the ceiling of a building, the ring or flange 1 will 40 be screwed to the ceiling, and the support B, of soapstone or similar material, is retained within the semicircular flanges 2 2. By plac-

ing these parts around the pipe C in the manner indicated they can be set closely to the pipe, and secured by screwing the stock A 45 firmly to the ceiling; or the pipe can be free to slide in said supports by having a small distance between the surface of the pipe and the soapstone or slate.

In the stock that is adapted to the floor, I 50 prefer to make use of pendent fingers 4, to pass down beneath and support the sectional or half rings B, of slate or similar material.

I do not claim a single rigid block of stone 55 or inferior conducting material, with a hole through the same for the passage of a stove-pipe; neither do I claim metallic supports for the same; and I am aware that a packing of asbestos, mineral wool, or similar material has 60 been placed around a steam-pipe and within a tube or socket. These devices are not adapted to use under the circumstances where my improvements are available, because the steam-pipes require to be led in the proper direction, and then non-conducting material 65 in separate pieces or sections introduced between the metallic support and the pipe itself, so that the pipe is free to expand and contract, and the pipe itself does not come directly into contact with the metallic support. 70

I claim as my invention—

The sectional flanged metallic support for steam-pipes, recessed around the pipe and provided with openings for the attaching-screws, in combination with soapstone or other non-conducting material in sections within the recess and separating the steam-pipes from the metallic support, substantially as specified. 75

Signed by me this 18th day of January, A. D. 1886.

W. A. LILLIENDAHL.
